UNITED STATES PATENT OFFICE.

HARRY W. MACDOUGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,272,689.

Specification of Letters Patent.

Patented July 16, 1918.

Application filed July 2, 1917. Serial No. 178,163.

To all whom it may concern:

Be it known that I, HARRY W. MACDOUGALL, a citizen of the United States, residing at East Orange, in the county of Essex and State of New Jersey, have invented certain new and useful Improvements in Telephone-Exchange Systems, of which the following is a full, clear, concise, and exact description.

10 This invention relates to telephone exchange systems, and more particularly to such systems in which ringing current is automatically applied to a wanted line upon the connection of a link circuit therewith.

15 An object of this invention is the production of improved signaling means for such systems.

Another object of this invention is the provision of a system of this character in 20 which it is impossible to ring a subscriber in the ear.

In accordance with this invention, a link circuit of the automatic ringing type is provided with apparatus for preventing the 25 connection of the source of ringing current to a busy line or a line the receiver of which is removed from the switchhook when the link circuit is connected with such a line. Apparatus is also provided, by means of 30 which, when the link circuit is connected to a line of the character mentioned, a signaling device is caused to furnish a characteristic signal indicating to the operator that the line to which the link circuit has been 35 connected is either busy or the receiver thereof is off its switchhook. Should it be desired to telephonically connect the calling line with the busy line, the actuation of a switch or key in the link circuit by the operator 40 stops the operation of the signaling device, and completes the talking circuit between the calling line and the busy line.

For a more complete understanding of 45 this invention, reference should be had to the following description, considered in connection with the accompanying drawing containing one embodiment thereof.

In the drawing, there is shown a calling 50 telephone line A, connected in any desired manner with a cord circuit C, which may be

employed to connect calling line A with another telephone line B. It will be understood that a number of lines similar to lines A and B, terminate at the same central office, and that a number of cord circuits are 55 provided thereat for interconnecting these lines, but, for the sake of convenience, only two lines and the one cord circuit are shown.

Assuming that the operator has been advised that the calling subscriber A desires 60 to be connected with subscriber B, the operator may test the terminal of line B in order to determine whether this line is idle or busy. Assuming that line B is busy, due to the connection of another cord circuit, 65 similar to C, with one of its jacks, the cut-off relay 5 of line B will be operated to disconnect the line relay 6 from the line. Under these conditions, the operator may insert plug 7 of cord circuit C into jack 8 without making a test. If the plug of the cord circuit C be inserted into the jack 8 while another cord circuit is connected with another jack of the same line, current will flow 70 from battery in the other cord circuit over 75 the ring talking strand thereof and the ring contacts of the engaged plug and jack, the ring contacts of the jack 8, and the plug 7, lower normal contact of relay 9, the windings of polarized relay 10, upper normal 80 contact of relay 9, tip contacts of the plug 7 and the jack 8 and back to the other side of battery in the cord circuit through the tip contacts of the other engaged jack and plug and the tip talking strand of the other 85 cord circuit connected to another jack of line B. Relay 10 is polarized so as not to attract its armature when its windings are traversed by current flowing in the direction just traced. The insertion of the plug 90 7 into the jack 8 causes the operation of relay 11 over a circuit from battery through the winding of relay 11, upon normal contact of relay 12, sleeve contacts of the plug 7 and jack 8, and the winding of cut-off relay 5 to ground. Relay 11, in operating, 95 opens its normal and closes its alternate contact. The opening of the normal contact of relay 11 introduces a break in the tip talking strand of the cord circuit C. The 100

closure of the alternate contact causes the intermittent operation of the calling supervisory lamp 13 over a circuit from battery through the lamp 13, alternate contact of relay 11, resistance 14, and interrupter 15 to ground. The intermittent operation of the calling supervisory lamp indicates to the operator that the cord circuit has been connected with a busy line. The operator may thereupon advise the calling subscriber that line B is busy, and withdraw the plug 7 from jack 8 and disconnect the cord circuit C from the calling line A.

In case, however, that lines of subscribers A and B had been previously connected together and had been accidentally disconnected before the conclusion of the conversation, the operator, upon connecting with line A, is advised that the connection between subscribers A and B has been accidentally severed. The operator will, therefore, immediately insert plug 7 into jack 8. Under these conditions, it may be that subscriber B has his receiver off the switchhook endeavoring to get the operator in order that connections may be reestablished with line A, so that, upon the insertion of the plug 7 into jack 8, the direction of the flow of current through the windings of polarized relay 10 is in the direction to operate this relay. However, since the receiver of line B is off the switchhook, the circuit, including the line wires and the low resistance bridge at the subscriber's station, forms a low resistance shunt in parallel with the winding of the polarized relay 10 and prevents the operation of this relay. Relay 11 operates as before, causing the intermittent operation of the supervisory lamp 13. The winding of relay 11 is of high resistance, so that when relay 11 is included in circuit with the cut-off relay 5, relay 11 operates but the cut-off relay 5 does not operate. In order that the talking circuit between lines A and B may, under these conditions, be completed, the operator momentarily actuates a non-locking key 20. Upon the actuation of this key, relay 12 is operated over a circuit from battery, through the lamp 13, winding of relay 12, upper alternate contact of key 20, and resistance 21 to ground. Relay 12, in operating, completes a locking circuit for itself from battery through lamp 13, winding of relay 12, upper alternate contact thereof, sleeve contacts of the plug 7 and jack 8 and the winding of cut-off relay 5 to ground. The cut off relay 5 now operates, disconnecting the line relay 6 from the line. Relay 12, in operating, causes the release of relay 11, whereupon the intermittent operating circuit for lamp 13 is opened. The lamp 13 is now continuously lighted over the circuit including relay 12 and the cut off relay 5. The

actuation of key 20 also causes the operation of relay 25 over a circuit from battery through resistance 26, lower alternate contact of key 20, normal contact of relay 25 and winding thereof, and the lower alternate contact of relay 12 to ground. Relay 25, in operating, closes its alternate and opens its normal contact, and establishes, through its alternate contact, a locking circuit for itself. The closure of the alternate contact of relay 25 also establishes a direct short circuit for ringing relay 27 preventing its operation. Relay 12, in operating, also causes the operation of relay 9, which opens its normal contacts, removing the polarized relay 10 from across the tip and ring contacts of the cord circuit, and closes its alternate contacts, completing the talking circuit between lines A and B. Immediately upon the operation of relay 9, the receiver at station B being off the switchhook, supervisory relay 28 operates to close a shunt circuit including a resistance 29 for the calling supervisory lamp 13, thereby extinguishing this lamp. Upon the conclusion of the conversation, the receivers are restored to their switchhooks, thereby causing lighting of the supervisory lamps to furnish disconnect signals to the operator, who may then disconnect the cord circuit from the lines, whereupon all apparatus is restored to normal condition.

If, when the plug 7 is inserted into the jack 8, the receiver at station B is on the switchhook, there will not then exist the hereinbefore mentioned low resistance shunt circuit about the polarized relay 10, but relay 10 does not operate until after the operation of relay 11, for while relay 11 remains in its normal position, there exists a low resistance circuit in parallel with the windings of relay 10. This circuit may be traced from the point 34 on the tip talking strand through the normal contact of relay 11, upper normal contact of relay 27, and repeating coil winding 33 to ground. Upon the operation of relay 11, which opens the low resistance parallel circuit, the polarized relay 10 operates over a circuit from battery through right-hand winding of line relay 6, right-hand normal contact of cut-off relay 5, tip contacts of the jack 8 and the plug 7, upper normal contact of relay 9, windings of relay 10, lower normal contact of relay 9, ring contacts of the plug 7 and the jack 8, left-hand normal contact of cut-off relay 5, and the left-hand winding of line relay 6 to ground. Polarized relay 10, in operating, closes its contact, thereby causing the operation of relay 12 over a circuit from battery through the lamp 13, winding of relay 12, contact of polarized relay 10, sleeve contacts of the plug 7 and the jack 8, and the winding of cut-off relay 5 to ground. Relay 12, in operating, completes the hereinbefore

traced locking circuit for itself, and the supervisory lamp 13 is lighted over this circuit which includes the winding of relay 12, and the winding of cut-off relay 5. Cut-off relay 5 now operates, disconnecting the line relay 6 from the line. Relay 12, upon attracting its armatures, also causes the operation of relay 9, which disconnects the polarized relay 10 from across the talking strands of the cord circuit, and closes the normally open contacts in the talking strands. Relay 12, in operating, also causes the operation of ringing relay 27 over a circuit from battery through the winding of relay 27, normal contact of relay 25, normal contact of key 20, normal contact of tripping relay 30, and the lower alternate contact of relay 12 to ground. Ringing relay 27, in operating, connects a source of ringing current 31 to line B, through the winding of tripping relay 30, for causing the operation of the usual call bell 32 at station B. Subscriber B, in responding to the operation of this call bell 32, removes the receiver from the switchhook, thereby causing the operation of tripping relay 30, which removes the short circuit from about relay 25. Relay 25 is thereupon included in circuit with the ringing relay 27, and is energized. Relay 25, upon being energized, closes its alternate and opens its normal contact. The closure of the alternate contact of relay 25 establishes a locking circuit therefor and completes a direct short circuit for ringing relay 27, which releases, disconnecting ringing current from the called line. Upon the release of ringing relay 27, supervisory relay 28 operates in the manner hereinbefore described to extinguish supervisory lamp 13. At the conclusion of the conversation, the supervisory relays release to cause the supervisory lamps to be lighted to furnish disconnect signals, whereupon the operator may disconnect the cord circuit C from the two lines, restoring all apparatus to normal condition.

What is claimed is:

1. In a telephone exchange system, the combination of a telephone line, a link circuit comprising a pair of talking conductors, a relay bridged across the talking conductors, an energizing circuit for the relay completed by the connection of the link circuit with the telephone line, a source of ringing current, and a relay operating upon the energization of the bridged relay for connecting the source of ringing current to the line.
2. In a telephone exchange system, the combination of a telephone line, a link circuit comprising a pair of talking conductors, a relay bridged across the talking conductors and energized upon the connection of the link circuit with the telephone line, a second relay operating upon the energiza-

tion of the bridged relay for disconnecting the bridged relay from the talking conductors, a source of ringing current, and a ringing relay operating upon the energization of the bridged relay for connecting the source of ringing current to the line. 65

3. In a telephone exchange system, the combination of a telephone line, a link circuit comprising a pair of normally open talking conductors, a relay bridged across the talking conductors and energized upon the connection of the link circuit with the telephone line, a second relay operating upon energization of the bridged relay, a locking circuit therefor established upon the operation thereof, a switching device rendered effective upon the operation of the second relay to disconnect the bridged relay from and to close the talking conductors, a source of ringing current, and a ringing relay energized upon the operation of the second relay for connecting the source of ringing current to the line. 70 75 80

4. In a telephone exchange system, the combination of a telephone line extending from a subscriber's station to a central office, a switch at the station adapted to close the telephone line, a link circuit at the central office comprising a pair of normally open talking conductors, a relay bridged across the talking conductors and energized upon the connection of the link circuit with the telephone line when the telephone line is open and not energized when the telephone line is closed, a signaling device, interrupter mechanism, and a relay operating upon the connection of the link circuit with the telephone line for including the interrupter mechanism in circuit with the signaling device to cause the intermittent operation thereof when the bridged relay is not energized. 90 95 100 105

5. In a telephone exchange system, the combination of a telephone line extending from a subscriber's station to a central office, a switch at the station adapted to close the telephone line, a link circuit at the central office comprising a pair of normally open talking conductors, a relay bridged across the talking conductors and energized upon the connection of the link circuit with the telephone line when the telephone line is open and not energized when the telephone line is closed, a signaling device, interrupter mechanism, a relay operating upon the connection of the link circuit with the telephone line for including the interrupter mechanism in circuit with the signaling device to cause the intermittent operation thereof when the bridged relay is not energized, a switching device, and a relay operating upon the momentary actuation of the switching device for causing the closure of the talking conductors. 110 115 120 125

4

6. In a telephone exchange system, the combination of a telephone line extending from a subscriber's station to a central office, a switch at the station adapted to close the telephone line, a link circuit at the central office comprising a pair of normally open talking conductors, a relay bridged across the talking conductors, and energized upon the connection of the link circuit with

10 the telephone line when the telephone line is open and not energized when the telephone line is closed, a signaling device, interrupter mechanism, a relay operating upon the connection of the link circuit with the telephone line for including the interrupter mechanism in circuit with the signaling device to cause the intermittent operation thereof when the bridged relay is not energized, a switching device, a local relay energized upon the momentary actuation of the switching device to stop the intermittent operation of the signaling device, and a disconnect relay operating upon the energization of the local relay to disconnect the bridged relay from and to close the talking conductors.

7. In a telephone exchange system, the combination of a telephone line extending from a subscriber's station to a central office, a switch at the station adapted to close the telephone line, a link circuit at the central office comprising a pair of normally open talking conductors, a relay bridged across the talking conductors and energized upon the connection of the link circuit with the telephone line when the telephone line is open and not energized when the telephone line is closed, a signaling device, interrupter mechanism, a relay operating upon the connection of the link circuit with the telephone line for including the interrupter mechanism in circuit with the signaling device to cause the intermittent operation thereof when the bridged relay is not energized, a switching device, a local relay energized upon the momentary actuation of the switching device to deenergize the second mentioned relay thereby to stop the intermittent operation of the signaling device, a locking circuit for the local relay established upon the operation thereof, and a disconnect relay energized upon the operation of the local relay to disconnect the bridged relay from and to close the talking conductors.

8. In a telephone exchange system, the combination of a telephone line extending from a subscriber's station to a central office; a switch at the station adapted to close the telephone line; a link circuit at the central office comprising a pair of normally open talking conductors; a relay bridged across the talking conductors and energized upon the connection of the link circuit with

the telephone line when the telephone line is open and not energized when the telephone line is closed, and means for closing the talking conductors upon the connection of the link circuit with the telephone line when closed comprising a switching device, and a relay energized upon the actuation of the switching device for causing the closure of the talking strands.

9. In a telephone exchange system, the combination of a telephone line extending from a subscriber's station to a central office; a switch at the station adapted to close the telephone line; a link circuit at the central office comprising a pair of normally open talking conductors; a relay bridged across the talking conductors and energized upon the connection of the link circuit with the telephone line when the telephone line is open and not energized when the telephone line is closed; means for closing the talking conductors upon connection of the link circuit with the telephone line when closed comprising a switching device, a relay energized upon the momentary actuation of the switching device, a locking circuit therefor established upon the energization thereof, and a disconnect relay operating upon the energization of the last mentioned relay to disconnect the bridged relay from and to close the talking conductors.

10. In a telephone exchange system, the combination of a plurality of telephone lines each terminating in a plurality of switching terminals, a plurality of link circuits having co-operating switching terminals each comprising a pair of talking conductors, a source of ringing current, a ringing relay in each link circuit for connecting the source of ringing current to a line upon the connection of the associated link circuit with a terminal thereof, a relay bridged across the talking conductors of each link circuit controlling the operation of the associated ringing relay, and means rendered effective upon the connection of one link circuit with a terminal of one of the lines for preventing the operation of the bridged relay of another link circuit when connected with another terminal of the same line.

11. In a telephone exchange system, the combination of telephone lines, each terminating in a plurality of switching terminals, a plurality of link circuits, having co-operating switching terminals, each comprising a pair of talking conductors, a polarized relay bridged across the talking conductors of each link circuit and operating upon the connection thereof with the terminals of one of the telephone lines, a source of ringing current, a ringing relay in each link circuit energized upon the operation of the polarized relay thereof for connecting the source of ringing current to the associated

line, and means rendered effective upon the operation of the polarized relay of a busy link circuit for preventing the operation of the polarized relay of another link circuit 5 upon the connection thereof with another terminal of the same line.

12. In a telephone exchange system, the combination of a telephone line, a link circuit comprising a pair of talking conductors, a relay bridged across the talking con- 10

ductors, an operating circuit for the relay completed by the connection of the link circuit with the telephone line, and a source of ringing current controlled by, and connected with the telephone line upon the operation 15 of, the relay.

In witness whereof, I hereunto subscribe my name this 29th day of June A. D., 1917.

HARRY W. MACDOUGALL.
